UNITED STATES PATENT OFFICE.

CHARLES W. OLSON, OF DETROIT, MICHIGAN, ASSIGNOR TO CONTINENTAL MOTORS CORPORATION, OF DETROIT, MICHIGAN, A CORPORATION OF VIRGINIA.

ASSEMBLING-CRADLE.

1,389,068.

Specification of Letters Patent. Patented Aug. 30, 1921.

Application filed February 16, 1920. Serial No. 358,987.

To all whom it may concern:

Be it known that I, CHARLES W. OLSON, a citizen of the United States, residing at Detroit, in the county of Wayne and State of Michigan, have invented a new and useful Improvement in Assembling-Cradles, of which the following is a specification.

My invention relates to assembling cradles intended for use where assembling operations are performed on apparatus traveling along tracks or runways. My invention is particularly applicable to devices of this kind where it is required at certain stages in the assembling operation to get at the bottom part of apparatus being assembled so as to perform required operations thereon, as for example, in assembling internal combustion motors.

My device provides a means by which the apparatus being assembled may move on the rollers or wheels on which it is mounted, along the tracks or runways, and have the necessary operations performed upon it successively during the course of which, when it is necessary to perform certain operations on the bottom of the apparatus, my device is employed to receive the trucks or wheels carrying the apparatus; means are provided for clamping the apparatus in place on the cradle and then by releasing the locking devices with which the cradle is provided, the cradle and the parts carried thereby may be rotated substantially ninety degrees in which position they may be positively and safely held without the danger of the apparatus falling from the cradle. By my invention I also provide devices for holding the cradle in its normal position for which the apparatus passing along the runway may stop on the cradle if it is required to perform operations on the bottom of the apparatus, or this motion may be continued along the runway without interruption, if it is not necessary to use the cradle.

My invention will best be understood by reference to the accompanying drawings showing a preferred embodiment thereof in perspective view.

As shown in the drawings, tracks 1 are shown in dotted lines as forming a part of a runway by which the apparatus may be brought to the cradle, and tracks 2 are similarly shown and form another part of the runway by which the apparatus may be removed from the cradle. The cradle consists

essentially of parallel tracks 3, 3 mounted on circular frame members 4 and 5 having outwardly projecting flanges 6 and 7 which rest in grooved supporting rollers 8 and 9 respectively, said rollers being supported by bases 10 and 11 from the floor so as to bring the sectional tracks 3 into alinement with the tracks 1 and 2.

The frame member 5 is provided at 12 with holes through it to receive the double locking bolt 13 pivotally connected at 14 with a foot lever 15. The lever 15 is pivotally connected at 16 with the back leg of the base 11, and projects through the front leg of said base and terminates in a foot pad 17 in position for convenient operation by the workman. A spring 18 holds the lever 15 in its upper position unless it is forcibly depressed. The front ends of the flanges 6 and 7 are enlarged radially as indicated at 6^a and 7^a, and forms stops for engaging the front rollers 8 and 9 to prevent rotation of the cradle beyond its position of alinement with the tracks 1 and 2. The enlargement 7^a has projecting therefrom a pin 19 engaged by a latch 20 pivotally supported at 21 on the housing of the front roller 9, said latch 20 being in the form of a bell crank lever, the other end of which is pivotally connected with foot lever 15, by a link 22. When the lever 15 is in its uppermost position, the latch 20 is in the position indicated in the drawing to engage the pin 19 to prevent rotation of the cradle.

When it is desired to rotate the cradle, the lever 15 is depressed, moving the locking bolt 13 from the holes 12, and at the same time moving the latch 20 from engagement with the pin 19. For this condition, the cradle is released and may be rotated on the rollers 8 and 9 until the enlarged ends 4^a and 5^a of the frame members engage the back rollers 8 and 9, which limits the rotation of the cradle. At this time a second pair of locking holes 23 formed in the frame member 5 come into alinement with the locking bolt 13, and by engagement of the locking bolt therewith, the cradle may be held in its rotated position as long as desired. The enlarged ends 4^a and 5^a may be of any desired size to serve as counterweights where the work being assembled is of a nature requiring some counterbalance to make the cradle easily rotatable when the apparatus being assembled is mounted thereon. A

brace rod 24 is disposed between the upper ends of the members 4 and 5 to brace them and hold them in proper relation to each other. After the operations required have been performed on the bottom of the apparatus, the foot lever is depressed and the cradle is rotated to bring it to normal position with its two sections of track 3 in alignment with the stationary sections of track. When 10 the rotation of the cradle has brought the enlarged flanges 6^a and 7^a against the front rollers 8 and 9, the latch 20 at once engages the pin 19 to prevent rebound of the cradle and also to prevent any tendency of the cradle to jump from the front rollers. The 15 engagement of the latch 20 also serves to hold the cradle in position so that the bolt 13 may enter the locking holes 12 thus securing the cradle against rotation until its rotation is again desired.

In the drawing I have indicated in dotted lines, diagrammatically a motor 25 in position on the cradle, it being held in said position by the rollers 26 so that it may be 25 moved along the tracks to place the motor in position on the cradle. To hold the motor in the position indicated on the cradle, I prefer to use clamping devices as indicated at 27 so as to prevent the motor or 30 other work being assembled, from falling off the cradle when rotating. These clamps extend from under the front rail 3 over any convenient part of the apparatus being assembled.

35 While I have shown my invention in the particular embodiment above described, I do not however limit myself to this exact construction in carrying out my invention, as I may employ equivalents thereof known 40 to the art at the time of the filing of this application without departing from the scope of the appended claims.

What I claim is:

1. In a device of the class described, the 45 combination of circular frame members, tracks secured to said frame members and extending between them, rollers supporting said members, and locking devices for holding said members in desired position on said 50 rollers, said members having outwardly projecting flanges and said rollers having grooves engaging said flanges.

2. In a device of the class described, the 55 combination of circular frame members, tracks secured to said frame members and extending between them, rollers supporting said members, and locking devices for holding said members in desired position on said 60 rollers, said locking devices comprising a foot lever, and a locking bolt connected therewith and extending into one of said frame members.

3. In a device of the class described, the 65 combination of circular frame members, tracks secured to said frame members and

extending between them, rollers supporting said members, and locking devices for holding said members in desired position on said rollers, said locking devices comprising a foot lever, a latch for engaging one of said members, and a link connecting said foot lever and said latch. 70

4. In a device of the class described, the combination of circular frame members, tracks secured to said frame members and 75 extending between them, rollers supporting said members, and locking devices for holding said members in desired position on said rollers, said members having outwardly projecting flanges and said rollers having grooves engaging said flanges, and said locking devices comprising a foot lever, and a locking bolt connected therewith and extending into one of said frame members. 80

5. In a device of the class described, the 85 combination of circular frame members, tracks secured to said frame members and extending between them, rollers supporting said members, and locking devices for holding said members in desired position on said 90 rollers, said members having outwardly projecting flanges and said rollers having grooves engaging said flanges, and said locking devices comprising a foot lever, a latch for engaging one of said members, and a link connecting said foot lever and said latch. 95

6. In a device of the class described, the combination of circular frame members, tracks secured to said frame members and 100 extending between them, rollers supporting said members, and locking devices for holding said members in desired position on said rollers, said locking devices comprising a 105 foot lever, a locking bolt connected with said lever for engaging one of said members, a spring connected with said lever tending to hold said bolt in locking engagement, a pivoted latch for engaging one of said members, and a link connecting said 110 latch and said foot lever.

7. In a device of the class described, the combination of circular frame members, tracks secured to said frame members and 115 extending between them, rollers supporting said members, and locking devices for holding said members in desired position on said rollers, said members having outwardly projecting flanges and said rollers having grooves engaging said flanges, and said locking 120 devices comprising a pivoted foot lever, a locking bolt connected with said lever for engaging one of said members, a spring connected with said lever tending to hold said bolt in locking engagement, a pivoted latch for engaging one of said members, and a link connecting said latch and said foot lever. 125

8. In a device of the class described, the combination of circular frame members, 130

- tracks secured to said frame members and extending between them, rollers supporting said members, and locking devices for holding said members in desired position on said 5 rollers, said locking devices comprising a foot lever, and a locking bolt connected therewith and extending into one of said frame members, said frame member having two positions of engagement with said bolt.
- 10 9. In a device of the class described, the combination of circular frame members, tracks secured to said frame members and extending between them, rollers supporting said members, and locking devices for holding said members in either of two positions 15 as desired on said rollers, said locking devices comprising a pivoted foot lever, a locking bolt connected with said lever for engaging one of said members in either of said positions, and a spring tending to hold 20 said bolt in engaging position.

In witness whereof, I hereunto subscribe my name this 2nd day of Feb., A. D. 1920.

C. W. OLSON.
